UNITED STATES PATENT OFFICE.

JENS S. SVENSEN, OF HAMMOND, INDIANA.

FOLDABLE CANVAS BOAT.

1,134,773.

Specification of Letters Patent.

Patented Apr. 6, 1915.

Application filed November 23, 1914. Serial No. 873,543.

To all whom it may concern:

Be it known that I, JENS S. SVENSEN, a subject of the King of Norway, residing at Hammond, in the county of Lake and State of Indiana, have invented certain new and useful improvements in Foldable Canvas Boats; and I do hereby declare the following to be a full, clear, and exact description of the invention, such as will enable others skilled in the art to which it appertains to make and use the same.

This invention relates to foldable waterproof boats designed for sportsmen, gunners, fishermen and others, and one of the principal objects of the invention is to provide a frame which can be taken apart and put together easily, said frame having a waterproof canvas cover, and the entire boat being made up to be disconnected and folded into a small package for carrying the same.

Another object of the invention is to provide a foldable canvas boat of durable construction, which can be quickly set up in position for use and which can be readily taken apart and folded for shipment or storage, and which will occupy but little space.

The foregoing and other objects may be attained by means of the construction illustrated in the accompanying drawings, in which,

Figure 1 is a side elevation of the frame of the boat, with the cover removed, Fig. 2 is a side elevation of the cover detached from the frame, Fig. 3 is a top plan view of the frame, Fig. 4 is a top plan view of a canvas cover having the various parts connected thereto in condition to be folded for carrying the same, shown broken away at one corner, and portions folded, Fig. 5 is a side elevation and a sectional view showing the manner of tying the cover to the frame of the boat, Fig. 6 is a side elevation of the parts packed and ready for carrying, and Fig. 7 is a plan view of the paddle.

Referring to the drawings, the numerals 1 designate two sticks or rods extending in an inclined direction in front to form the bow of the boat or scow, said rods or sticks being connected at their upper ends to a coupling 2, while their lower ends are connected to a three-way coupling 3. Extending across the bow of the boat is a similar rod or stick 4 extending into the coupling 2 or into a nipple 5 of the coupling 2, as shown more clearly in Fig. 3. The sticks or rods forming the bottom and top of the side frames of

the boat are connected by means of similar couplings 6, 7, 8, 9, 10 and 10^a and cross rods 11, 12 and 12^a are secured to the couplings 6, 8 and 10^a while vertical rods or sticks 13 and 14 are connected to the two couplings 7, 9 and 8, 10, shown in Fig. 1. At the stern the couplings 15 are angular and are connected by uprights 16 and cross rods. Seats 17 and 18 are provided with cleats to prevent them moving on the upper rails or rods ^a. A suitable paddle *b* is provided with a detachable handle *c* connected to the paddle by means of a sleeve *d*, as shown in Fig. 7.

The cover 19 is formed from oiled or waterproof canvas and is made to fit the frame and is provided along the upper edge with perforations 20, and other perforations running parallel to the perforations 20, as indicated by the numeral 21. The cover 19 is secured to the side rails *a* at the top of the frame by means of cords or ropes, as shown in Fig. 5. The edges of the canvas are turned over the side rails so as to allow the perforations 20 and 21 to register. The cords or ropes 22 are passed through the perforations 20 and 21 and extend underneath the rails *a*, and are then reeved through, as shown in Fig. 5 and made fast at the ends.

For holding the various parts of the boat together for packing the same into a small space, the piece of canvas or other flexible cover 19 is shown partially folded in Fig. 4 as indicated by the numerals 24 and 25. 90 Pockets 26 are provided for the sticks or rods, and pockets are also provided for the seats 17 and 18. A separate pocket 27 is provided for the coupling members or connections for the rods.

When the boat is to be taken apart, the various parts are connected to the cover 19 and folded up and made into a package, as shown in Fig. 6, said package having straps 28 connected by a handle 29 to readily carry the same.

From the foregoing it will be obvious that a boat made in accordance with this invention can be readily carried by a sportsman or person having a camping outfit, and the boat 105 can be easily assembled whenever desired, and is light, durable and efficient for its purpose.

Various changes may be made in the details of construction without departing from 110 the spirit and scope of the invention as defined in the claims.

What is claimed is:—

1. A collapsible water proof boat made up of rods connected together by couplings to form a boat shape frame and a water proof fabric cover for said frame provided with pockets for the rods, the couplings and other attachments for the boat, said cover being foldable to occupy but little space for carrying the same.
- 10 2. A collapsible boat made up of rods and couplings therefor to form a scow shape

frame, a cover of water proof canvas adapted to be connected to said frame by tying the cover to the frame at the upper edge thereof, and pockets on said cover for the 15 cross rods, seats and couplings.

In testimony whereof I affix my signature in presence of two witnesses.

JENS S. SVENDSEN.
